JOHN H. WILLIAMS, OF ESSEX, CONNECTICUT, ASSIGNOR TO HIMSELF,
THOMAS N. DICKINSON AND WILLIAM E. BEAMES.

Letters Patent No. 79,712, dated July 7, 1868.

IMPROVEMENT IN THE MANUFACTURE OF FLOOR-CLOTH.

The Schedule referred to in these Letters Patent and making part of the same.

TO ALL WHOM IT MAY CONCERN:

Be it known that I, JOHN H. WILLIAMS, of Essex, county of Middlesex, and State of Connecticut, have invented a new and useful Improvement in the Method of Covering or Painting Floor-Cloth; and I do hereby declare the following to be a full, clear, and exact description of the same, reference being had to the accompanying drawings, and to the letters of reference marked thereon; said drawings constitute part of this specification, and represent, in—

Figure 1, the side view of my improvement.

Figure 2, a plan view of the same.

Figure 3 is a cross-section, showing the spring-plates open for the reception of the cloth.

Figure 4 is a cross-section, showing the spring-plates drawn together and cloth inserted.

Similar letters of reference, when they occur in the different views, indicate like parts.

My invention relates to an improvement in the method or manner of mechanically filling, covering, or painting floor-cloth, and consists of a machine in which the cloth, after being passed through the paint, is carried between or under one or more sets of spring-plates, or their equivalents, which press the paint into the cloth, and also give it a peculiarly smooth surface; whereas, in the method now used for thus preparing floor-cloth, a great amount of time and labor has to be expended upon the cloth after it is filled or painted, to obtain the proper smoothness of surface to allow of its being printed and finished.

To enable others skilled in the art to make and use my invention, I will proceed to describe the construction and operation of the same.

A is a vat or trough, in which the paint, after being properly prepared, is contained. Held in movable bearings, and sliding vertically in the same trough A, a roll, B, is placed, the object of which is to immerse the cloth in the paint.

C C are two spring-plates, or their equivalents, constructed of steel, or other suitable material, arranged to swing, or otherwise, as convenient, and adjusted or drawn together by means of thumb-screws, a, or other convenient devices, between which said plates the cloth passes after leaving the vat or trough A, the object of these plates being to regulate the amount or quantity of paint upon the cloth, and distribute the same evenly over the surface, notwithstanding the unevenness of said cloth.

D D are two spring-plates, or their equivalents. The lower of said plates is held stationary, or otherwise convenient; the upper one swings on bearings, and is operated or pressed down upon the under plate by means of lever b, or other convenient device. Between these two plates the cloth is passed in order to smooth and polish the same.

This completes the construction of my improvement. The operation is as follows:

First, the requisite amount of properly-prepared paint is placed in the vat or trough A; the cloth is then introduced and passed under the roll B, to allow of which, the said roll is raised above the surface of the paint, as shown in fig. 3. The said roll is then lowered to a sufficient depth in the vat or trough to thoroughly immerse the cloth in the paint. After this the cloth is drawn, first between the two spring-plates C C, said plates being brought together by means of the thumb-screws a, and pressed against the cloth, which give them the curve, as shown in fig. 4. This curve in these plates gives the cloth, as it passes, a peculiar drawing-pressure, and instead of simply scraping the paint from the surface, distributes it evenly over it, without regard to the unevenness of the cloth. After the cloth has passed between the two said plates, C C, it is drawn forward over the roll F and between the other set of plates D D. These said plates are similar to the said plates C C, except that they are made longer, for the reason that they are intended for smoothing and finishing the surface instead of removing the superfluous quantity of paint therefrom. These plates may be pressed together and against the cloth by means of lever b, or other convenient device, as shown in fig. 4.

A great advantage of these spring-plates is, that when any unevenness, wherever it may occur in the cloth

that passes between them, the said spring-plates adjust themselves to it in that particular place, while all around it the surface will be as smooth as if it had been perfectly even ; whereas, in a smoother which is held without a spring, the unevenness is either torn away or else the smoother, in being raised to clear it, make a ridge or uneven place the whole width of the cloth, which has to be smoothed before the cloth can be painted.

The peculiar advantage, however, is the curving of the plates, by which the cloth, as it passes, is given a drawing or smoothing motion, similar to that given to plaster by a trowel.

I am aware that this curvature may be given to a rigid surface of metal or wood, and may be used to advantage in the place of the springs herein described, but as this curvature renders their action similar, as far as the drawing-pressure is concerned, to the spring-plates, I have not considered it necessary to describe any other particular method of construction.

I do not confine myself exclusively to the use of springs, or any number of springs, between which the cloth passes, for if one side of said cloth is to be finished, only one plate will be required. This plate will be constructed and operated in the same manner as those described, the cloth resting the opposite side upon a roller or plain surface.

Having thus fully described my invention, what I claim as new and useful, and desire to secure by Letters Patent, is—

1. The spring-plates C C, or their equivalents, for distributing the paint evenly over the surface of the cloth, and also remove the extra amount of the same, substantially in the manner and for the purpose specified.
2. The spring-plates D D, or their equivalents, as a smoothing-device, for the purpose of finishing the cloth, substantially as herein described.
3. The peculiar curve of the plates herein described, when in operation, constructed of springs, or their equivalents, to give the smooth and polished surface to the cloth as it passes through the machine, in the manner described and for the purpose specified.

JOHN H. WILLIAMS.
